UNITED STATES PATENT OFFICE.

GLENN E. BLINN, OF PHILADELPHIA, PENNSYLVANIA, ASSIGNOR OF ONE-HALF TO
GROVE P. MITCHELL, JR., OF PHILADELPHIA, PENNSYLVANIA.

AUTOMATIC SIGNAL DEVICE.

1,175,405.

Specification of Letters Patent. Patented Mar. 14, 1916.

Application filed September 6, 1913. Serial No. 788,431.

To all whom it may concern:

Be it known that I, GLENN E. BLINN, a citizen of the United States, residing in the city and county of Philadelphia, State of Pennsylvania, have invented a new and useful Improvement in Automatic Signal Devices, of which the following is a specification.

My invention relates to those devices that are used in large establishments, factories, department stores, hotels, etc., for locating persons in the building who might be wanted at the office, and has for its object not only to enlarge the work to be performed by such a device by applying it as a signal to employees to start and stop work and to locate the point at which a fire is burning in the building and give the necessary alarm, but also to produce a more perfect and accurate machine for such purposes. I accomplish these objects by means of the instrument presently described and particularly shown in the accompanying drawings forming part hereof, and in which,—

Figure 1 is a perspective view of the machine, showing particularly the kick-off coils and cam arrangement for tripping the holding-plate. Fig. 2 is an end view of the same. Fig. 3 is a view of the other end of the machine showing the means for operating the shaft carrying the disks; and the magnetic coils and their connection with the disks for sounding a fire alarm. Fig. 4 is a diagram of the electric circuit that operates the machine and sounds the signals. Fig. 5 is a plan view of my machine. Fig. 6 is an elevation of the back plate of the key-board. Fig. 7 a view of the end piece of said board supporting the pivoted lever which is operated upon by the armature of the kick-off coils and which trips the holding plate, Fig. 8 being a side view of the same. Fig. 9 a view of the opposite end of said board supporting armature and a contact-spring. Fig. 10 an edge view thereof. Fig. 11 is a view of a key or plunger in operative position in contact with a disk, and showing the contact plate in operative position with the contact-spring, thus closing the circuit and putting the machine in operation. Fig. 12 is a view of such key or plunger in inoperative position, the contact-plate out of operative position with the spring, thus breaking the circuit and bringing the machine to rest. Fig. 13 is a front elevation of the key-hold-

ing plate; and Fig. 14 an end view of the same. Fig. 15 is a front elevation of the contact-plate; and Fig. 16 an end view thereof. Fig. 17 is a side elevation of a disk carrying pins; and Fig. 18 an edge view of the same. Fig. 19 is a side elevation of the sprocket-wheel forming one of the elements in the automatic cut-out; and Fig. 20 an edge view thereof.

Similar letters and numerals of reference designate corresponding parts throughout the several views.

My invention consists, in the first place, of a frame which is preferably made up of foundation 1, supports 2 and 3 connected at their tops by a reinforcing rod 4, and provided with laterally-extending brackets 5 and 6 adapted to receive and support the key or plunger board. Journaled in supports 2 and 3 is a shaft 7 which is electrically operated by a motor A through a worm-wheel B on motor shaft C intermeshing with sprocket-wheel D on perpendicular shaft E journaled in bearings E' and E'' attached to the support; said shaft E carrying at its upper end a worm-wheel F which intermeshes with sprocket-wheel G carried by said shaft 7. Upon shaft 7 are removably-secured one or more disks 8, the same being adapted to be slid upon said shaft which enters a central opening 9 in the disks and which are then located upon and affixed to the shaft by means of a screw 9 $\frac{1}{2}$ passing through the collar 9 $\frac{3}{4}$ encircling said opening and pressing upon the shaft; this arrangement permitting of the removal of the disks from the shaft, or placed upon the same at will; the object being to increase or diminish the number of disks in accordance with the number of individuals to be located; or the number of fire alarm stations desired. With reference to the locating individuals, the periphery of these disks is provided, at regular intervals, with pin-holes 10 adapted to receive and retain pins 11. These holes and pins are so constructed that the latter can be easily inserted and extracted from the former, notwithstanding the fact that said pins are sufficiently embedded in the holes as not to fall out or become loosened except by force being applied to them. The removability of the pins permits the changing of numbers designating the individuals to be called or located without removing the disk from the shaft.

It will be obvious that instead of separate disks secured to a shaft, I can use a cylinder H (Fig. 5) and likewise arrange holes on its surface for the reception of pins, without departing from the spirit of my invention. I denominate these holes and pins peripheral pins and holes to distinguish them from the rim holes and pins hereafter described.

- 10 My improved key or plunger-frame consists of front and back plates 12 and 13 provided with one or more holes 14 registering with the disks 8; and end pieces 15 and 16 so formed that the key-board can be slid on and off the brackets 5 and 6 of the supports 2 and 3, the said key-board resting between and being supported by said brackets as shown in Figs. 2 and 5; that is, the said end pieces are provided on their outer faces, at 20 the top and bottom, with grooves 15' and 16' forming between them flange 15² and 16². The board or frame is thoroughly insulated from the brackets upon which it rests by suitable insulating material α which is secured by suitable means to said brackets upon their inner faces and so formed as to permit the board to be easily slid into position, the body of the insulating material filling the grooves 15² and 16² of the said 25 end-pieces and extending up and down between the beads 15' and 16', respectively, and the brackets 5 and 6, thus forming a bearing at its top for the said board to rest upon, as shown particularly in Fig. 1. Of course any other suitable construction whereby the board is effectually insulated from the brackets will be within the scope of my invention as I do not confine myself to the construction shown and described. 30 Also, while this key-board is preferably constructed so that it can be removed from the machine, it is obvious that it can be permanently fixed in the same without in the least affecting the novelty of my device. 40
- 45 17 designates the keys or plungers which are mounted in the board and adapted to move backward and forward in the holes 14. They consist of an elongated piece of suitable material, preferably brass, and preferably cylindrical in form, and are provided with a head 17^a, and two ribs 17^b and 17^c, the former conical in shape as shown; and pivoted in one end is a contact pin 18 provided with a beveled side 18^a. These plungers or keys are mounted in the frame in the 50 holes 14 with the pin 18 adjacent the disks 8, the bevel 18^a up and so that when the keys are in operative position, the pins 11 carried by the disks will strike said contact 18 as the disks revolve, the contact, being pivoted, giving way and allowing the disk-pins to pass; which pins, as they strike the contact 18, close the circuit and cause the signal to be noted at all the stations in the 55 building. A spring 19 is carried by each

plunger, one end of which spring bears upon the back plate 13 of the key-board, while the other end bears against the rib 17^c of the plunger itself; said spring operating normally to retain the plunger out of striking distance of the disk-pins 11 when the plunger is not in action; or when the machine is inactive. These plungers or keys are designated station keys.

Extending the length of the key board 75 and pivoted therein, is what I term the holding-plate 20 provided with flange 21 on its upper edge; the function of this plate is to hold the plunger or key in operation within striking distance of the disk-pin 11 by 80 means of the flange 21 which drops behind and bears against the conical rib 17^b of the plunger, the plate 20 rising as the plunger is pushed forward allowing said rib to pass under and stopping just in front of the 85 flange 21 and preventing the key from moving backward. Likewise pivoted within said key-board is another plate which I will call the contact-plate 22, which is pivoted at its bottom edge and retained in a perpendicular and inoperative position by a spring 23; this plate carries at one end a contact-pin 24 which is adapted, when the upper free edge of the plate 22 is pushed forward by the conical-rib 17^b of the plunger, to contact 90 with a spring-contact 25 secured in the end piece 16 of the key-board, which contact 25, being electrically connected, closes the circuit and puts the motor A in operation and through it, the shaft carrying the disks. In Fig. 11 is shown the position of the plunger and of the plates 20 and 22 when the machine is in operation. And in Fig. 12 they are shown in inoperative position and the machine at rest.

The above description, as will be observed, delineates the structure of the machine and its operation up to its being put in motion. That is, we will say, the machine being electrically connected by a series of wires to 110 gongs (not shown) or other sounding apparatus located at different points in a building, and the pins 11 on the disks 8 being so arranged as to transmit the number 32 throughout said building, the plunger opposite the disk carrying this number, and the person wanted having been designated 32, said plunger is pushed forward into striking distance of said pins 11 and held there by plate 20; at the same instant the 115 top of contact-plate 22 is moved forward by said plunger causing the pin 24 to engage the contact-spring 25, thereby closing the circuit through the key-wire 102—103 to battery 100 and motor A; thence, through 120 wire 104—101 to the key 17; the motor A being thus electrified, the shaft 7 is actuated through the worm-wheel B on shaft C intermeshing with sprocket wheel D on perpendicular shaft E, worm-wheel F inter- 125 130

meshing with sprocket-wheel G carried by said shaft 7, thereby bringing the disk into operation, the pins 11 on which, striking the pivoted pin 18 of the plunger 17 in operation, the number 32 is sounded throughout the building through wire 113 and signal-bell 109, the contact between the pins and the pin 18 of the key 17 closing the circuit through wire 102—103 to battery 100, through wire 108 to the bell 109 and to disk through wire 113 and the person so numbered repairs to the nearest telephone and answers the call. (See Fig. 4.)

I will now proceed to describe the methods of stopping the machine after the person called has responded thereto. These are three in number, to wit, at the station or machine by means of the major key; at the telephone to which the person called goes to answer the signal by means of a push-button located there (not shown) which is electrically connected with the kick-off coils of the machine; and automatically by mechanism attached to the machine and which can be set to stop the machine after the signal has been sounded a determined number of times. In each case the holding-plate 20 is lifted and the plunger in operation released, its spring 19 instantly driving the plunger back out of operative contact with the pins on the disk, the contact-plate 22 being, at the same time, pulled by its spring 23 from contact with the spring 25, breaking the circuits and causing the machine to stop. First, the major key 26 is slidably mounted in the key-board 12 and, as it is pushed forward, operates to raise the plate 20 as the rib on said key moves under the flange 21 thereon. This rib does not go beyond said flange as the key 26 is so arranged that it can be pushed forward only far enough to permit its rib to pass beneath the flange 21 so as to raise the plate 20 and allow the station-key it is holding to escape; the spring on the key 26 causing it to instantly return to its inoperative and out-of-the-way position. This, together with the fact that plate 22 is always in its operative or forward position (as shown in Fig. 12) when it is necessary to use the key 26, avoids any interference between the key 26 and said plate 22. While the rib on the key will contact with and push forward said plate, it will do so only when the latter is out of action and there can be no result from such contact not only because the key 26 can not hold the plate 22 in such forward position owing to its inability to advance beyond the plate 20, but because there can possibly be no connection between said key and the disks on the shaft. As described, the only function of this key 26 is to lift the plate 20, and it can have none other. Secondly, the push-button 105 at the telephone is electrically connected with the kick-off coils 27

through wire 106 to wire 107—108 to battery 100, wire 112—114 to button 105; these coils are provided with armature carrying arm 28 which is adapted, when the button 105 is pushed closing the circuit, to spring 70 forward and strike the lever 29 pivoted on end-piece 15; which lever, swinging forward at its lower and free end, causes its arm 30 to rise sharply striking the holding plate 20, lifting it, thereby releasing the station-key in operation, as before stated. The third and last way of tripping the holding-plate 20 is automatic and is accomplished by means of mechanism consisting of a cam 31 secured to one end of shaft 7, the point 80 of which cam, upon the revolution of said shaft, engages cam-wheel 32 mounted on support 3 adjacent said cam. The face of this wheel is provided with pin-holes 33 at regular intervals apart, into which holes 85 one or more pins 34 are inserted, the inner ends of which extend beyond the face of the wheel (see Fig. 20) and which ends are adapted, when the wheel 32 is revolved by the cam 31, to strike the pivoted arm 35 of lever 36, tripping it, which, in turn strikes the arm 28 of the lever 29, tripping it also; which, as in the other two cases, strikes up the plate 20 and releases the plunger in operation. The series of holes 33 and the pins 95 allow of determining the number of times the signal is to be sounded before tripping the levers and breaking the circuits. In order to hold the cam-wheel 32 taut and firm, I pivot to the support 3 one end of a 100 dog 40; sustaining the free end of said dog in contact with the wheel by a spring 41, and providing the dog at its said free end with an arm 42, which is adapted to rest in the grooves between the teeth with which 105 the periphery of the wheel 32 is provided, as is shown in Figs. 1 and 2.

To permit the machine to be used to sound an alarm of fire and locate the same, I arrange on the rim of disks 8, pins 37; and adjacent each disk, on the opposite side of the machine from the key-board, I place magnetic coils or relays 38 provided with a trip-contact 39 carrying a spring 45 adapted, when the circuit is closed, to contact with 110 the pins 37 on the disks as the same revolve. There is a relay or coil for each fire-alarm station—No. 1 station being mounted directly back of No. 1 disk in the machine; No. 2 station relay back of No. 2 disk; and 115 so on. On each floor of a building, or in each department, there is a break-glass fire-alarm box 110, electrically connected with its respective relay and disk. Should a fire start, some one on the particular floor, or in 120 the particular department, breaks the glass in the said box 110 which throws the spring-contacts therein into contact with each other thereby closing the electric circuit between the box 110 and the coils or relay 38 for that 125 130

station; the relay thus becoming energized, its trip-contact 39 is pulled to the pole-piece of the relay bringing the spring 45 into contact with the pins on the disk which, at the 5 same instant, starts to revolve by reason of the electric current being thrown to the motor A as well as to the bells throughout the building giving every one therein prompt and efficient warning. At first the signal is 10 given by single strokes in rapid succession; then the bells are quiet for a second or two, then strike one, two, three times, as the case might be, to indicate the floor or department; the signal then continues at intermittent 15 though constant impulses as the spring 40 contacts with the pins 37 on the rapidly revolving disks, and will not cease until the fire-alarm box which has been broken is closed for future use. In case the machine is 20 in operation when a fire starts, the breaking of the glass in the box 110 and the closing of the circuit at coils 38, will at the same moment operate the kick-off coils 27 through the two point contacts at the rear of said 25 coils 38, the operation of the kick-off coils 27, as before described, throwing the station key out of action. The complete circuits operating when the glass in box 110 is broken which throw out of action, through the 30 kick-off coils 27, any station-key that may be in use, and throw into operation the fire-alarm system, are as follows: the kick-off coils circuit being from conductor 107 through wires 108-117 to batteries 100; from here through wire 112 to contacts of 35 coils 38; through same to wire 116 then to coils 27; out of these to wire 107. The starting of the motor is through batteries 100, wire 117 to motor A; from thence through 40 wires 118-115 and trip contact 39 to contacts of coils 38; through same to wires 108-112 back to batteries 100. It will of course be understood that the method of 45 wiring to bring about these results forms no part of my invention but is entirely within the discretion of the electrician installing the system and in accordance with the well known rules of the science.

The same equipment can be used where a 50 building has each floor wired and heat coils distributed at various places on the ceiling, the heat from the fire opening the heat-coil, and closing the electric circuit in the same manner as when the glass in a fire alarm box 55 is broken. It can also be used where a building is equipped with a sprinkler system where a float valve is installed on each floor of a building. The setting off of a sprinkler head, either by a fire or by accident, starts 60 the water flowing in the pipes, causing the float valve to close the electric circuit and start the machine and in the same manner sound the alarm through the machine, giving the floor or department location of the 65 open sprinkler head and hence the fire.

Having now described my invention, what I claim as new and desire to secure by Letters Patent, is:—

1. In an automatic signal device, a frame; a shaft mounted therein; one or more disks 70 on said shaft; pins carried by said disks adapted to be removed therefrom; a removable key-board mounted in said frame in juxtaposition to said disks; plungers in said board adapted to contact with the pins on the disks when the same are revolved; and means for revolving said disks, substantially as shown and described.

2. In an automatic signal device, a frame; a shaft mounted in said frame; one or more 80 disks on said shaft; pins carried by said disks adapted to be removed therefrom; means for operating said shaft; a removable key-frame mounted in said frame adjacent said disks; plungers in said board adapted 85 to contact with the pins on the disks when the same are revolved; and means in said board for holding said plungers in contact with said pins.

3. In an automatic signal device, a frame; a shaft mounted in said frame; means for operating said shaft; one or more disks carried by said shaft; removable pins on said disks; a removable key-board mounted in said frame adjacent said disks; plungers 95 mounted in said board adapted to be moved in contact with said pins; means in said board for holding said plungers in contact with said pins; and means carried by said plungers for throwing them out of such contact when said plungers are released, substantially as shown and described.

4. In an automatic signal device, a frame; a shaft mounted in said frame; means for operating said shaft; one or more disks carried by said shaft; removable pins on said disks; a removable key-board mounted in said frame adjacent said disks; plungers mounted in said board adapted to be moved in contact with said pins; means in said 100 board for holding said plungers in such contact; means carried by said plungers for throwing them out of such contact when said plungers are released; and means for releasing said plungers, substantially as 105 shown and described.

5. In an automatic signal device, a frame; a shaft mounted in said frame; means for operating said shaft; one or more disks carried by said shaft; removable pins on said 110 disks; a removable key-board mounted in said frame adjacent said disks; plungers mounted in said board provided at their inner ends with a pivoted point adapted to contact with said pins and so arranged as 115 to permit of the disks revolving in one direction and preventing them from revolving in the opposite direction, substantially as shown and described.

6. An automatic signal device consisting 120

- of a frame, a shaft mounted therein; means for operating said shaft; one or more disks carried on said shaft; pins in said disks; a key-board in said frame adjacent said disks; 5 plungers mounted in said board adapted to be moved into contact with said pins; means for holding said plungers in such contact; and means for operating upon said holding means to throw the same from said plungers.
- 10 7. An automatic signal device consisting of a frame; a shaft journaled in said frame; electrical means for operating said shaft; one or more disks carried by said shaft; pins removably fixed in said disks; a removable 15 key-board mounted in said frame adjacent said disks; plungers in said board adapted to be moved in contact with said pins; a plate pivoted in said board adapted to hold said plungers in said contact; a lever pivoted in said board provided with an arm adapted to strike said plate and throw it from contact with said plungers; a spring on each plunger adapted to throw it from contact with said pins; and electrical means 20 for tripping said lever, substantially as shown and described.
8. An automatic signal device consisting of a frame; a shaft journaled in said frame; electrical means for actuating said shaft; 30 one or more disks carried by said shaft; pins removably secured to said disks; a removable key-board mounted in said frame adjacent said disks; plungers mounted in said board adapted to be moved in contact with 35 the pins on said disks but provided with a spring normally to hold them out of such contact; a plate pivotally mounted in said board adapted to hold said plungers in contact with said pins; a lever pivoted to said board provided with an arm adapted to strike said plate and throw it from contact with said plungers; a second lever pivoted on said frame adapted to strike the first lever and trip it; a cam wheel pivoted to the 40 frame adjacent said second lever arranged to revolve in but one direction and carrying means for tripping said lever; and a cam carried by the shaft and adapted to engage said wheel and actuate it at intervals; substantially as shown and described.
- 50 9. An automatic signal device consisting of a frame; a shaft journaled in said frame; electrical means for actuating said shaft; a disk carried by said shaft; pins on said disk; an electric coil adjacent said disk provided with an armature which, when a current of electricity is applied, will be thrown in contact with the pins on the disk, substantially as shown and described.
- 55 60 10. An automatic signal device consisting of a frame; a shaft journaled in said frame; electrical means for actuating said shaft; a disk on said shaft carrying pins; an electric coil adjacent said disk; armature so arranged that when electrically actuated through said coil will contact with said pins, substantially as shown and described.
11. In an automatic signal device, a frame; a shaft mounted in said frame; electrical means for operating said shaft; one or more disks carried by said shaft; removable pins on said shaft; a removable key-board mounted in said frame adjacent said disks; plungers mounted in said board adapted to be moved in contact with said pins; means pivoted in said board for holding said plungers in such contact; a spring carried by each plunger for throwing them out of such contact when said plungers are released; and electrical means for releasing 75 80 said plungers, substantially as shown and described.
12. An automatic signal device consisting of a frame; a shaft journaled therein electrically actuated; one or more disks carried by said shaft; pins in said disks so arranged that when contacted by electrical means intermittent signals will be given at any point in a building.
13. In an automatic signal device, a frame, a shaft journaled therein electrically actuated; a cam carried by said shaft; a cam-wheel pivoted on said frame adjacent said cam and so as to receive from it an intermittent or alternating motion as the shaft 95 revolves; pins carried by said cam-wheel; a lever pivoted on said frame adjacent said cam-wheel adapted to be tripped by said pins as the cam-wheel revolves; and a second lever mounted in the frame adapted to be 100 tripped by said first lever.
14. In an automatic signal device, a frame in which is journaled a shaft electrically actuated and carrying one or more disks; a key-board removably mounted in 105 said frame in which is movably arranged one or more plungers or keys; a spring contact arranged in said board; a plate pivoted in said board adapted to contact with said contact when operated upon by said 110 plungers, substantially as shown and described.
15. In an automatic signal device, a frame in which is journaled a shaft electrically actuated and carrying one or more 115 disks, and a key-board removably mounted in said frame adjacent said disks in which is movably arranged one or more plungers or keys adapted to contact with said disks, substantially as shown and described.
16. An automatic signal device consisting of a frame, a shaft journaled therein electrically operated, disks on said shaft carrying pins, electric coils adjacent said disks provided with armatures so constructed and arranged that said armatures will contact with said pins as the disks revolve and means for operating said shaft.
17. An automatic signal device consisting of a frame, a shaft journaled therein electric- 120 125 130

cally operated, disks carried by said shaft provided with pins, electric coils adjacent said disks having armatures adapted to contact with said pins as the disks revolve, and means for starting and stopping said shaft and means for operating said shaft.

18. An automatic signal device consisting of a frame; a shaft journaled therein electrically actuated; disks carried by said shaft; pins in said disks; a key-board in said frame; plungers mounted in said board adapted to be pushed into contact with said pins; a plate pivoted in said board adapted to hold said plungers in such contact; a cam carried by said shaft; a cam-wheel pivoted on said frame so as to receive from said cam

an intermittent motion as the shaft revolves; pins carried by said cam-wheel; a lever pivoted on said frame adapted to be tripped by the pins on the cam wheel as the same revolves; a second lever mounted in said frame adapted to be tripped by said first lever and adapted to strike up the said holding plate whereby the plungers are released and permitted to spring back out of contact with the pins on the disks, substantially as shown and described. 20 25
